UNITED STATES PATENT OFFICE.

BENJAMIN CHARSKY, OF BROOKLYN, NEW YORK.

LUNCH KIT.

Application filed July 1, 1921. Serial No. 481,840.

To all whom it may concern:

Be it known that I, BENJAMIN CHARSKY, a subject of Russia, residing in the borough of Brooklyn, county of Kings, city and 5 State of New York, have invented a certain new and useful Lunch Kit, of which the following is a specification.

The invention relates to fitted lunch kits in which may be carried not only food and 10 beverages, but a service consisting of the necessary table ware.

Some of the objects of the invention are to provide an article of the character described which will be compact in form; 15 which will have great carrying capacity in proportion to its size, in which the comestibles will be kept in a separate compartment from the service; which may be opened flat whereby all of the articles carried thereby will be accessible; which is sanitary and may be readily cleaned; which when closed will entirely enclose the elements carried thereby, and wherein all of the fixtures will be securely held in position 20 in the device.

Another object of the invention is to provide a lunch kit which, when opened, may be utilized as a table.

A further object of the invention is the 25 production of a device, of the character herein described, which is extremely simple in construction, neat and attractive in appearance, thoroughly reliable and efficient in its purpose, and economical to manufacture.

With these and other objects in view to be more fully set forth hereinafter, the invention consists in the novel construction, combination of elements, and arrangement 30 of parts which will be exemplified in the construction hereinafter described in the specification and illustrated in the accompanying drawings considered together or separately.

45 The inventive idea involved is capable of receiving a variety of mechanical expressions, one of which, for the purpose of illustrating the invention, is shown in the accompanying drawings.

50 The invention will be first described in connection with the accompanying drawings, wherein similar reference characters are used to designate corresponding parts throughout the several views, and then more specifically defined and indicated in the appended claims.

In the drawings:—

Figure 1 is a front elevation of the device, showing the same in closed position.

Figure 2 is an end elevation of the same. 60

Figure 3 is a horizontal section taken on the line 3—3 of Figure 1.

Figure 4 is a detail section, on an enlarged scale, taken on the line 4—4 of Figure 3. 65

Figure 5 is a plan view of the device in open position.

Figure 6 is a detail sectional view of a portion of the device illustrating the manner in which the sandwich box is secured 70 in position, and

Figure 7 is a section on the line 7—7 of Figure 6.

The invention comprises a bag or case, 75 preferably made of leather or other suitable material, in a form which suggests the well-known portfolio or brief case. It consists of a bottom portion 1, a front portion 2, a rear portion 3, a top portion 4 and securing flap 5.

The body of the device is divided into a front compartment and a rear compartment as follows:

The end portions 6 of the front or comestibles compartments are somewhat narrower than the bottom portion 1, and said end portions are carried outward in the forms of flaps 7 adapted to be bent over inward to overlap at the center and be secured together as by snap fastenings 8. The 90 end portions 6 are provided with tabs 9, which are adapted to be bent inward when the kit is closed, whereby there will be no corner openings in the said front portion. 85

The end portions 10 of the rear or service compartment are preferably somewhat narrower than the portions 6, the sum of the widths of the portions 6 and 9 being equal to the width of the bottom portion 1. The portions 10 are extended to form 100 flaps 11 which may be folded over and secured in position in the same manner as are the flaps 7.

The front flap 5 may be secured to the front portion 2 in any desired manner, as 105 by a lock 12 and buckled straps 13, or in any approved manner.

The inside of the entire apparatus is preferably covered with a sanitary covering 14 of oil cloth or the like which may be easily 110 washed.

To the inside of the front portion 2 at

the bottom edge thereof, and in proximity to each end thereof is secured by rivets or otherwise, a right angle bracket 15. The free legs of the brackets extend perpendicular to the position 2 and the outer ends thereof are provided with angle slots 16 with which are adapted to cooperate studs 17 projecting from one side of a sandwich, or other food, container 18. The studs are 10 provided with heads, and the container 18 is positioned by passing the studs downward into the vertical portions of the slots and then moving the box sidewise to engage the studs in the horizontal portions of the slots. 15 The parts are so proportioned that one at least of the side members 6 cannot be folded up against the end of the box while the studs are in, or in line with the vertical portions of the slots 16. The container 18 is 20 provided with a hinged cover 19 which may be secured in closed position by any desired means, or the flaps 7 may be relied upon to hold the cover 19 closed.

The container 18 is not of a width sufficient to occupy all of the space on the front compartment 2. A loop 20 is secured to the portion 2, and nested drinking vessels 21 are carried in the said loop. A liquid receptacle, such for example as a vacuum bottle 22 is carried in a loop 23, one end of which is stitched to the front member, and the other end of which is secured in place by means of snap fasteners. The loop may carry a plurality of snap fastener members 35 whereby bottles of different sizes may be carried.

Secured to the center of the inside of the back member is a loop arrangement 24 by means of which plates and napkins may be 40 secured in position. The back also carries loops 25 and 26 for carrying cutlery and condiment boxes.

The top portion 4 is equipped with a carrying handle 25, but it is to be understood 45 that any other carrying means may be provided.

When the device is to be used, it is spread out upon the ground, as shown in Figure 5. The entire device, especially the flaps 5, 7, 50 and 11 and the front portion 2 and the top 4 are used as a table, the sanitary lining 14 being uppermost. When the meal is finished and the dishes washed, the lining may also be easily washed whereby the entire device 55 may be kept in sweet, clean and sanitary condition.

It is obvious from the foregoing disclosure and description that the device is a unique combined lunch kit and table.

60 In accordance with the provisions of the patent statutes, I have described the principle of my invention together with the apparatus which I now consider to represent the best embodiment thereof, but I desire 65 it understood that my invention is not con-

fined to the particular form of apparatus herein shown and described, the same being merely illustrative, and that the invention can be carried out in other ways without departing from the spirit of my invention, and, therefore, I claim broadly the right to employ all equivalent instrumentalities coming within the scope of the appended claims, and by means of which objects of my invention are attained, and the new results accomplished, as herein set forth, as it is obvious that the particular embodiment herein shown and described is only one of many that can be employed to attain these objects and accomplish these results.

Having now described my invention what I claim and desire to secure by Letters Patent is:

1. In a kit holder; the combination with an envelope of pliant material having a central portion adapted to form the bottom and side members, and projecting flaps adapted to form the top and end members of a substantially rectangular receptacle produced by folding said envelope; of a rigid rectangular container and brackets secured to the envelope, said brackets having attaching means adapted to unite with complementary attaching means on the container, whereby said container is positioned and secured with edges coincident with fold lines defining the bottom of said receptacle.

2. In a kit holder, the combination with an envelope of pliant material having a central portion adapted to form the bottom and side members, and projecting flaps adapted to form the top and end members of a substantially rectangular receptacle produced by folding said envelope; of a rigid rectangular container, and means to secure said container within the envelope said means adapted to unite with complementary securing means on the container, said container having its edges coincident with the fold lines defining the bottom of said receptacle.

3. In combination with a receptacle of a folded fabric, of the folded pliant envelope type, a rectangular rigid container and brackets secured to the envelope, said brackets having attaching means adapted to unite with complementary attaching means on the container whereby said container is positioned and secured with edges coincident with the fold lines defining one of the narrower sides of said container, whereby a flat, rigid, narrow supporting base is provided for said receptacle.

4. In a kit holder, an envelope of pliant material, having a central portion forming the bottom and side members and projecting flaps forming the top and end members of a substantially rectangular receptacle produced by folding said envelope, of a rigid rectangular container and brackets secured

to the envelope, said brackets having attaching means adapted to unite with complementary attaching means on the container, whereby said container is positioned and secured with edges coincident with the fold lines defining the bottom of said receptacle, and a pair of opposite tabs projecting from each of the two of the flaps adjacent the juncture of said flaps with said central portion, said tabs being adapted to be turned inward to close corner openings when said envelope is folded to produce said receptacle.

This specification signed this 25 day of June, 1921.

BENJAMIN CHARSKY.
